Attorney.

UNITED STATES PATENT OFFICE

EDWARD H. FABRICE, OF CHICAGO, ILLINOIS, ASSIGNOR TO GUARDIAN SAFETY SEAL COMPANY, OF CHICAGO, ILLINOIS, A CORPORATION OF ILLINOIS

BOTTLE SEALING CAP

Application filed January 24, 1931. Serial No. 511,011.

This invention relates to improvements in bottle sealing caps of the type having a skirt portion which is spun upon and into annular formations on a bottle neck and includes an annular ribbon of metal, commonly known as a "rip-strip", which is readily torn out of said skirt portion, thereby to sever the said skirt portion from the crown portion of the cap thus permitting the bottle to be unsealed.

10 The invention is applicable to that type of said sealing caps which is used to cover the sealing cork inserted into the bottle neck, as well as to that type of cap known as a screw-cap which contains a disk of cork or other 15 sealing material which is compressed upon the mouth of the bottle neck to seal the same, this latter type of cap being also frequently termed a "re-sealing" cap.

The main objects of the present invention are: first, to provide in the cap a rip-strip or severable ribbon which terminates in a free tongue so shaped as to prevent the fingers of the hand grasping the same from coming into contact with and being cut 25 or torn by the sharp burrs along the edges of said tongue; second, to provide a free tongue or digitally engageable end portion of the rip-strip which is normally shaped so that its side edge portions stand sufficiently 30 far out from the body of the cap to be primarily engaged by a finger-nail to bend it outwardly sufficiently to permit said free tongue to be engaged between finger tips preparatory to severing the ribbon from the 35 cap; third, to so form the said free end or tongue portion as to enable the finger tips to obtain a very firm hold thereon and also to render the same ornamental in appearance; fourth, to provide means associated with the 40 free tongue portion of the rip-strip which will prevent said tongue from becoming accidentally distorted in the handling of the bottles equipped with said caps; and, fifth, to obviate the necessity of punching or cutting 45 out small portions of the metal cap bordering the tongue in order to render the same digitally engageable without the preliminary use of a tool and thereby also preventing clogging of dies by said cut out metal.

50 Other objects and advantages of the in-

vention are hereinafter particularly pointed out.

In the accompanying drawing illustrating suitable embodiments of the invention:

Fig. 1 is a perspective view of a bottle neck 55 equipped with a cap constructed in accordance with the invention.

Fig. 2 is a central longitudinal section of the bottle neck and cap on the line 2—2 of Fig. 1.

Fig. 3 is a plan section of the same on the line 3—3 of Fig. 2.

Fig. 4 is a side elevation of a bottle neck equipped with thread formations and with a screw cap constructed in accordance with 65 the invention.

Fig. 5 is a plan section on the line 5—5 of Fig. 4.

The cap 1 of Figs. 1, 2, and 3 is a substantially cylindrical cup-like structure adapted 70 to be disposed upon the mouth portion of a bottle neck 2 which has been previously sealed by insertion of a cork or other seal 3, the lower end portion of the circumferential wall or skirt portion 4 of said cap 75 1 being suitably spun into close or hugging contact with annular formations on the bottle neck 2, such as the bead 5 and groove 6 below the latter.

The annular rip-strip or severable ribbon 80 7 of the cap 1 is integral with the skirt portion thereof and is bordered almost throughout its length by a pair of parallel scorings 8 which effect a thinning of the sheet metal of the cap, thus very appreciably weakening 85 the same.

Said severable ribbon or rip-strip 7 terminates at one end in a digitally engageable tongue element 9 which is completely severed from the body of the skirt portion by means 90 of an incision 10 which is in the form of a loop whose extremities are flush with the scorings 8. In the instance illustrated in Fig. 1, the said tongue element 9 is substantially circular and terminates in a short 95 stem 11 which may be defined as constituting an integral part of the rip-strip 7. The tongue element 9 is offset outwardly from the plane of the skirt portion sufficiently to permit finger nails to be inserted behind said

tongue element to permit the latter to be bent outwardly for engagement between finger tips. In the instance illustrated, the said tongue element is embossed with a monogram 5 which, besides being ornamental and serving, for example, the purposes of a trade-mark, also serves to provide formations which permit firmer finger tip hold on said tongue and thus to render the latter more easily operable 10 to tear out the rip-strip from the cap.

The offset of the tongue element from the body of the skirt portion is, however, apt to cause accidental distortion of said tongue element in the handling of the bottle as in 15 packing and unpacking the same, placing it on a display shelf, handing it to a customer, etc. To prevent this, I provide a guard formation 12 which, in the instance illustrated, consists of an arcuate embossing substantially 20 concentric with the tongue element and terminating at the scorings 8 or stem portion 11 of said tongue element 9. Said formation 12 projects farther from the body of the skirt portion of the cap than the width of the free 25 space between the inner face of said tongue element and the plane of the outer surface of the skirt portion of the cap. Said formation 12 is also ornamental, as will be obvious.

In the screw-cap structure of Figs. 4 and 30 5, the crown portion of the cap 13 is equipped with thread formations 14 to engage similar formations on the bottle neck 15.

The skirt portion 16 of the cap 13 is provided with the annular rip-strip 17 immediately 35 below the thread formations 14 and is bordered by the scorings 18 and terminates in the tongue element 19 which is only slightly wider than the rip-strip 17 and is formed with embossed parallel ribs 20 along its side 40 edges. The said tongue element 19 is also initially offset outwardly from the body of the skirt portion 16, similarly to the tongue element 9 of Figs. 1, 2, and 3 and for the same purpose. Said tongue element 19 is also severed 45 from the body portion of the skirt 16 by a loop-like incision.

Owing to lack of space around the tongue element 19, the guard formation for performing the function of the formation 12 of 50 Figs. 1, 2, and 3, consists of a boss 21 in the rip-strip 17 adjacent its other end and proximate to the extreme free end of the tongue element 19.

The formations 12 and 21 function apparently 55 equally well to prevent the said extreme free end of the tongue element from catching the clothing of persons handling the bottles equipped with said caps and thus becoming distorted.

The present invention affords certain manufacturing advantages in that the tongue elements are rendered free to be digitally engaged without requiring any of the metal bordering the same to be removed. This 60 operation, which is effected in other caps with

cutting dies, has been very troublesome because of the dies becoming dull and causing clogging of the female die. In the instant structures, the tongue elements are severed from the stem by a purposely dulled edge die 70 which serves to prevent the tongue edges from having sharp burrs which easily cut and tear the fingers.

In the present structures, the metal cut away to provide a slot bordering the tongue element is retained and made a part of the tongue, thus to greatly increase its size with the obvious advantages incident thereto.

I claim as my invention:

1. A bottle sealing cap including a substantially cylindrical skirt portion equipped with an annular rip-strip integral with said skirt portion and terminating at one end in a free tongue, and an outwardly projecting guard formation in said cap contiguous to said tongue for preventing accidental engagement and distortion of the latter in ordinary handling of a bottle equipped with said cap.

2. A bottle sealing cap including a substantially cylindrical skirt portion equipped with an annular rip-strip integral with said skirt portion and terminating at one end in a free tongue, the latter equipped with outwardly projecting formations affording firm digital engagement with said tongue, and an outwardly projecting guard formation in said cap contiguous to said tongue for preventing accidental engagement and distortion of the latter in ordinary handling of a bottle equipped with said cap.

3. A bottle sealing cap including a substantially cylindrical skirt portion equipped with an annular rip-strip integral with said skirt portion and terminating at one end in a free tongue, the latter equipped with outwardly projecting formations affording firm digital engagement with said tongue, the latter being normally outwardly offset from the adjacent portion of the skirt portion of the cap, and an outwardly projecting guard formation in said cap contiguous to said tongue for preventing accidental engagement and distortion of the latter in ordinary handling of a bottle equipped with said cap.

4. A bottle sealing cap including a substantially cylindrical skirt portion equipped with an annular rip-strip integral with said skirt portion and terminating at one end in a free tongue of greater width than said rip-strip and bent to smaller radius than said skirt portion, thereby normally offsetting the middle portion of said tongue outwardly from the latter a distance sufficient to permit finger nail insertion behind said cap, and an outwardly projecting guard formation in said skirt portion contiguous to said tongue for preventing accidental engagement and distortion of the latter in ordinary handling of a bottle equipped with said cap.

5. A bottle sealing cap having a substantially cylindrical skirt portion adapted to be formed to fit annular formations on the bottle-neck to permanently secure said skirt portion to said neck, an annular rip-strip integral with and disposed between the ends of said skirt portion for severing the latter, said rip-strip terminating in a free tongue bent to curvature of smaller radius than said skirt portion for causing said tongue to project outwardly from the said skirt portion sufficiently to permit finger-nail engagement therewith, and an outwardly projecting guard formation in the skirt portion of said cap 10 opposite the free end of the said tongue for preventing accidental distortion of said tongue.

6. A bottle sealing cap having a substantially cylindrical skirt portion adapted to be formed to fit annular formations on the bottle-neck to permanently secure said skirt portion to said neck, an annular rip-strip integral with and disposed between the ends of said skirt-portion for severing the latter, said 15 rip-strip terminating in a free tongue bordered by an incision of dimensions and contour substantially coinciding with those of the said tongue, the latter bent to curvature of smaller radius than said skirt portion for 20 causing said tongue to project outwardly from the said skirt portion sufficiently to permit finger-nail engagement therewith, and an outwardly projecting guard formation in the skirt portion of said cap opposite the free 25 end of the said tongue for preventing accidental distortion of said tongue.

In testimony whereof, I have hereunto set my hand this 21st day of January, 1931.

EDWARD H. FABRICE.
